WALL SAFE CABINET

Joachim Koch, Peterstr. 81-83, Aachen, Germany

Filed June 4, 1965, Ser. No. 85,576

Claims priority, application Germany Dec. 4, 1964

Term of patent 14 years

(Cl. D69—1)

FIG.1

FIG.2

FIG.3

FIG.4

FIGURE 1 is a front perspective view of a wall safe cabinet showing my new design, the rear being plain and unornamented;

FIGURE 2 is another front perspective view thereof showing the cabinet doors in an open position;

FIGURE 3 is a third front perspective view thereof showing both the cabinet and safe doors in an open position; and

FIGURE 4 is a fourth front perspective view thereof showing both the cabinet and safe doors in another open position.

I claim:

The ornamental design for a wall safe cabinet, as shown and described.
